MACHINE FOR MAKING PLASTER OF PARIS
BANDAGES

Jerome Weiss, Brooklyn, N. Y.

Application October 9, 1935, Serial No. 44,194

1 Claim. (Cl. 33—129)

This invention relates to improvements in a device for the manufacture of surgical bandages carrying plaster of Paris or other similar acting composition. Such bandages which are usually made up into rolls are used for preparing plaster casts. One way of making the bandages consists in sending or pulling a strip of bandage through a pile of plaster held in a container. The strip is unwound from a large roll of crinoline, passed through the plaster and then wound into another roll when loaded with the plaster. One form of a device for accomplishing this is shown in my Patent No. 1,981,607, dated November 20, 1934.

Where a large roll of crinoline is used, the strip of bandage is cut off from the roll when the required length has been run through the plaster. For certain purposes, a short length, say 2 yards is required for the loaded bandage, and for others a longer length, say 10 yards, is preferable. It is an object of my present invention to provide a device for making plaster of Paris bandages, which device has means for indicating the length of loaded bandage wound up in the finished roll.

Other objects and advantages will become apparent upon further study of the description and drawings, in which:—

Fig. 1 is a plan view of my device, no plaster being in the receptacle.

Fig. 2 is an end elevation of the device, as in Fig. 1, with part of the sidewall broken away and a pile of plaster shown in the receptacle.

Fig. 3 is a rear elevation of the device, looking along the line 3—3 of Fig. 1.

Fig. 4 is a front elevation of the indicating mechanism shown by itself, a portion only of the supporting arm being shown.

Fig. 5 is a section through the indicating mechanism taken along the line 5—5 of Fig. 4.

Fig. 6 is a section taken along the line 6—6 of Fig. 5.

Fig. 7 is a view of the dial shown by itself, and Fig. 8 is a view of the window dial by itself.

A number of different types of mechanism may be used for loading the bandage with plaster and winding it into a roll, which mechanism is combined with the mechanism for measuring and indicating the length of bandage passed through the machine and wound into a roll.

The particular mechanism, chosen for the purposes of illustration, for loading the bandage and winding it into a roll, as described herein, is that given in my above mentioned patent.

As described in said patent, the device con-

sists of a box or receptacle 6 containing a pile of plaster 30. The sidewalls of box 6 are held together by staybolts 7. Extending between the sidewalls are guide rods 10, 11, 12, 13, 14 and 15. The floor of the box is formed of a curved sheet metal plate 18.

At one end of the machine there is mounted a supporting arm 19, which has spool 24 rotatably mounted upon it. Crank 26 is fixed to spool 24 for rotating it. Fastened to the other end of box 6 is a bracket 33 having a shaft 39 fixedly mounted upon it.

Upon the right staybolt 7, right as seen in Fig. 2, is rotatably mounted a sleeve 40 having fixed to it a sheet metal arm 41. The upper end 15 of arm 41 is flattened out at 42 where it is fastened by welding to the rear face of casing 45 of the indicating mechanism. A stop sleeve 44 is fixedly mounted on staybolt 7 adjacent sleeve 40 to prevent axial motion of the latter. The front face of casing 45 is provided with a window opening 46. Immediately behind said opening is located a transparent sheet 47 of celluloid or other suitable material which is fixed to the inside of the casing. In the center of window opening 46, an index line 48, extending radially, is marked on sheet 47. Inward of the frontwall of casing 45 is a window dial 49 fixedly mounted on a sleeve 50 which is attached to knob 51. Said sleeve is loosely mounted on shaft 52 which in turn is rotatably mounted in bearing 53 on auxiliary casing 54 at one end and supported at the other in said sleeve and the hub of gear 55. Said sleeve is rotatably and frictionally mounted in the front wall of casing 45 and the hub 35 is rotatably mounted in the rear wall of said casing. To the rear of window dial 49 is a graduated chart or dial 56 fixedly mounted on the hub of gear 55 which in turn is fixed to shaft 52. Gear 55 meshes with pinion 57 fixed to shaft 40 58 which is rotatably mounted in the rear wall of casing 45 and in bearing 59 on auxiliary casing 54. Worm wheel 60 is fixed upon shaft 61 fixed to shaft 62. Shaft 62 is rotatably mounted in the right wall 45 (as viewed in Fig. 6) of auxiliary casing 54, and in bearing 63 fixed to the left wall of said casing. Fixed upon the outer end of shaft 63 is a sharp toothed wheel 65.

When not in operation, the measuring mechanism is swung to the left about right hand staybolt 7, as seen in Fig. 2 where it is shown in dot and dash lines on its way to inoperative position.

In operating the device, a roll of crinoline 29 55

is mounted on shaft 39, the crinoline strip 28 being led from said roll under guide rods 10 to 15. Clips 64 hold roll 29 against lateral motion on shaft 39, through plaster 30 to spool 24 upon which it is wound by means of crank arm 26. The measuring mechanism is swung about right hand staybolt 7 so that toothed wheel 65 rests upon crinoline roll 29. As will readily be seen, the rotation of wheel 65 is caused by the rotation of roll 29, and is in accordance with the travel of the crinoline strip 28. Rotation of wheel 65 causes rotation of graduated dial 56 through the train of gearing previously described.

15 The diameter of wheel 65 is such in relation to the gear ratios between the gears of the gear train, that when said wheel causes the rotation of graduated dial 56 the distance between two consecutive graduations in zone 66 on said dial, 20 it corresponds to a motion of 2 yards for a point on the periphery of wheel 65. When dial 56 is caused to rotate the distance between two consecutive graduations in zone 67, there is a corresponding motion of 3 yards for a point on the 25 periphery of wheel 65. In a similar manner the rotation of dial 56 between two consecutive graduations in zones 68, 69 and 70 corresponds to a motion respectively of 4, 5 and 6 yards for a point on the periphery of wheel 65. Zones 66 to 70 are 30 concentric.

Window 71 in window dial 49 comes opposite zone 66 of graduated dial 56. Similarly windows 72, 73, 74 and 75 come opposite zones 67, 68, 69 and 70 respectively.

35 When it is desired to load a roll of bandage 2 yards in length, knob 51 is turned to bring window 71 opposite window 46 in the front wall of casing 45. This permits the graduations in zone 66 only to be exposed through window 46, said 40 graduations being for 2 yard lengths. The front face of window dial 49 is preferably black, so that the light colored face of dial 56 stands out by contrast. With wheel 65 held clear of crinoline roll 29, said wheel is turned by hand to bring a 45 graduation in zone 66 in line with index line 48. Wheel 65 is then placed against roll 29. After

fastening the free end of the bandage strip to spool 24, as described in my above mentioned patent, crank 23 is turned until the crinoline has rotated wheel 65 enough to cause dial 56 to bring the next graduation in zone 66 opposite index line 48. The operator may then cut off the strip near spool 24 and will thereby have available a plaster of Paris roll of bandage, 2 yards in length.

For a 3 yard roll window 72 is set opposite window 46, and for a 4, 5 or 6 yard roll, window 10 73, 74 or 75 respectively is set opposite window 46. In each case when dial 56 has been rotated the distance between two consecutive graduations in the exposed zone, a length of bandage has passed through the machine corresponding in 15 length to the length indicated by said distance for the particular zone.

Other arrangements of the graduations and windows could be used, as will be understood by those skilled in the art.

While the claim specifies plaster of Paris, it is to be understood that it is intended to cover other powdered substances which set and harden by hydration and are suitable for bandages.

I claim:—

A device for indicating the length of bandage passing through a machine for coating said bandage with plaster of Paris, comprising a part contacting the bandage and rotated in accordance with the passage of the bandage through the machine, a dial having graduations arranged in a plurality of concentric zones, the graduations for each of said zones indicating a predetermined length of bandage passed through the machine, a given circumferential distance along the outermost zone corresponding to less length of bandage passed through the machine than said distance in the next succeeding inner zone, said length being successively less for each succeeding zone toward the center, and index means for indicating the graduations in a predetermined zone, said dial and index means being mounted for relative motion with respect to each other, said relative motion being effected by said part.

JEROME WEISS.
